TWO-STAGE ALKYLATION WITH OLEFIN STREAMS CONTAINING PROPYLENE AND ETHYLENE

Charles Ovid Baker, Dallas, Tex., assignor, by mesne assignments, to Socony-Vacuum Oil Company, Incorporated, New York, N. Y., a corporation of New York

Application April 19, 1946, Serial No. 663,389

5 Claims. (Cl. 260—683.4)

1

This invention relates to an improved process for effecting the alkylation of light olefins. More particularly, the invention relates to the economical recovery and utilization of the light olefins contained in dilute C₃ and lighter hydrocarbon gas streams for the production of high octane motor fuel.

Processes for the alkylation of light olefins, particularly ethylene and propylene, are well known but have not been adopted extensively primarily because of the difficulty of concentrating these olefins. Ethylene and propylene are available in large quantities in refinery gases from cracking units, and are also fairly readily obtainable by the cracking of propane or a mixed ethane-propane gas stream. From all of these sources, however, the concentration of the olefin is relatively low, generally considerably less than 50% on a mol or volume basis. The separation and concentration of these olefins for use in conventional alkylation reactors requires expensive, low-temperature-fractionation equipment. Absorption has been proposed, but this also involves an additional processing step and is effective in removing only methane and hydrogen, although these represent the main objectionable diluents.

In my copending application, Serial No. 618,972, filed September 27, 1945, there is disclosed a process whereby the alkylation of an isoparaffin, such as isobutane, with the light olefins contained in dilute gas streams, is combined with the absorption of the light olefins from the gas stream. The combined alkylation-absorption step is effected by employing the isoparaffin to be alkylated as the absorption menstruum and by the use of a soluble catalyst dissolved in the liquid isoparaffin menstruum. However, by the process disclosed in the copending application, the alkylate product obtained is a mixture of the alkylate products obtained from the individual olefins contained in the dilute gas stream, and for many purposes it is desirable to obtain the alkylate products from the individual olefins substantially free of admixture with each other. For example, for many purposes it is desirable to obtain ethylene-isobutane alkylate, consisting largely of 2,3 dimethyl butane, substantially free of propylene-isobutane alkylate, consisting largely of heptanes.

It is an object of this invention to provide an improved process for the utilization and recovery of light olefins in dilute gas streams. It is another object of this invention to provide a process for the alkylation of light olefins contained in dilute C₃ and lighter hydrocarbon gas streams. It is another and primary object of this invention to provide a process for the alkylation of light olefins contained in dilute C₃ and lighter hydrocarbon gas streams and recovery of the

2

alkylate products of the individual olefins substantially free of admixture with each other. It is another object of this invention to provide a process whereby C₂ alkylate substantially free of C₃ alkylate is obtained from a dilute C₃ and lighter hydrocarbon stream. Further objects and advantages of the invention will become apparent from the following description thereof.

In accordance with the invention, a C₃ and lighter hydrocarbon gas stream containing light olefins is subjected to combination alkylation-absorption to selectively alkylate first the heavier molecular weight olefin, propylene, and recover the alkylate product thereby obtained and then to alkylate the lower molecular weight olefin, ethylene, and separately recover the alkylate product thereby obtained. It has been discovered that higher molecular weight olefins will alkylate an isoparaffin, such as isobutane, in the presence of an active metal halide, such as aluminum bromide, at a more rapid rate than will a lower molecular weight olefin. Furthermore, by variation in reaction conditions such as temperature, pressure, or catalyst concentration, the difference in the rates of alkylation of a higher molecular weight olefin and a lower molecular weight olefin can be further increased. Thus, by subjecting a dilute gas stream containing propylene and ethylene to combination absorption-alkylation, the propylene will alkylate the isoparaffin absorption menstruum containing the catalyst at a more rapid rate than will the ethylene, and, in the first stage of the absorption-alkylation operation, reaction of practically all of the propylene and of a small proportion of the ethylene may be effected, while in the second stage of the operation only a small proportion of the propylene will be present in admixture with the ethylene, and the alkylate product from this stage will consist substantially entirely of ethylenealkylate. This is of particular advantage when employing isobutane as the isoparaffin absorption menstruum, since the ethylene alkylate product consisting largely of 2,3 dimethyl butane is a highly desirable aviation fuel constituent from the standpoints of octane rating, volatility characteristics, and lead susceptibility, and admixture with heavier alkylate is desirably avoided.

In carrying out the invention, a single absorption-alkylation column may be employed wherein the propylene alkylate may be removed from the bottom of the column and the ethylene alkylate removed at a point intermediate to the bottom and top of the column by collecting on a trap-out tray, for example. However, in order to obtain more perfect control of the reaction conditions for selective propylene alkylation, particularly with respect to pressure, it is preferred to employ two separate absorption-alkylation

columns. Any suitable type of absorption apparatus may be employed for the first column, such as a packed column or a bubble plate column. For the second column, an absorber of the bubble plate type is preferred because longer contact times are desirably employed for absorption-alkylation of ethylene, and these contact times can be more readily attained when using a bubble plate column. By suitable control of the contact time in the second absorption-alkylation column, the ethylene alkylation reaction may be substantially complete by the time the absorbed ethylene and isoparaffin-catalyst solution leaves the column. Sufficient time for complete reaction may be obtained by the use of time tanks between the plates, for example. Where sufficient time for complete reaction is not obtained, a small conventional reaction vessel may be employed to effect the necessary additional contacting of the ethylene dissolved in the reaction mixture.

As mentioned above, the combined alkylation-absorption steps are effected by employing the isoparaffin to be alkylated as the absorption menstruum and by the use of a soluble catalyst dissolved in the absorption menstruum. The catalyst employed should be soluble in the isoparaffin in effective concentration at the conditions prevailing in the absorbers, and any degradation products of the catalyst should be of a fluid or soluble nature, so that they will be carried out of the absorption reactors with the rich absorption menstruum-alkylate mixtures. Aluminum bromide is a suitable catalyst, having considerable solubility in light paraffin hydrocarbons at normal and moderately elevated temperatures. Additionally, the hydrocarbon complex tar that is slowly formed by side reactions in the alkylation steps is of a light fluid nature and will be largely carried out of the absorption-reactors with the liquid effluents from which it may be removed by gravity settling for recovery and regeneration.

My invention may be best understood by reference to the drawing wherein the essential steps in one mode of operation are diagrammatically illustrated. A gas stream containing ethylene and propylene in admixture with light paraffins, as methane, ethane, and propane, and hydrogen is introduced through line 10 into the base of absorber 11 packed with a suitable packing material 12, such as Raschig rings. An isobutane solution of aluminum bromide containing minor amounts of alkylate product and heavier saturated hydrocarbons obtained in a manner herein-after described, is introduced into the top of the absorber through line 14. The alkylation-absorption reaction is exothermic and, to maintain the desired temperature in tower 11, the tower may be provided with suitable cooling means (not shown), such as cooling coils, etc. Conditions of catalyst concentration, temperature, ratio of isoparaffin to propylene, and contact time of liquid per theoretical equilibrium contact space are maintained in absorber 11 in order to obtain maximum conversion of propylene and minimum conversion of ethylene contained in the gas stream. Suitable conditions are: catalyst concentration—1.2% by weight of isobutane; temperature—60° F.; pressure—100 p. s. i. a.; contact time of liquid per theoretical equilibrium contact space of absorber—8.2 seconds; mol ratio of isobutane to propylene dissolved therein—40 to 1.

The gas ascends upwardly through the column counter-currently contacting the downwardly

flowing stream of isobutane whereby the propylene under the reaction conditions maintained is converted substantially entirely to alkylate product. Only a small portion of the ethylene reacts, and the remainder passes as overhead from the absorber 11 through line 15 as a constituent of the lean gas, which now contains, in addition to the ethylene, a relatively minor proportion of unreacted propylene and substantially all of the methane and hydrogen and substantial portions of the ethane and propane contained in the original stream.

Rich liquid effluent leaves the absorber 11 through line 16 and contains excess isobutane absorbent, isobutane-propylene alkylate, some isobutane-ethylene alkylate, some absorbed but unreacted ethylene, traces of unreacted propylene, and some propane, ethane, and methane. This effluent in line 16 is sent to a flash evaporator 17 where the light gases and most of the isobutane and alkylate are taken off as overhead through line 19. The bottoms from the evaporator 17, consisting of a concentrated solution of the aluminum bromide catalyst in the unvaporized isobutane-alkylate liquid, are taken off through line 20 and passed to gravity settler 21. Tar is removed through line 22, and the aluminum bromide concentrate solution is passed through line 24 to line 14 for admixture with isobutane and reuse in tower 11. The relatively small amount of alkylate product contained in the recycled aluminum bromide concentrate solution has no material effect on the absorption-alkylation reaction.

The overhead from the evaporator in line 19 is then sent to a suitable fractionating column 26 for separation of the light gases which are discharged through line 27. The isobutane is separated from the propylene-isobutane alkylate product in fractionator 28 and recycled after condensation (not shown) to line 14 via line 25. The alkylate product is drawn off from the fractionator 28 through line 30 for final stabilization and treatment.

The overhead gas from absorber 11 passing through line 15 contains, in addition to unreacted ethylene, a portion of unreacted propylene, and the remaining light paraffinic constituents of the original gas stream, a portion of isobutane which has been vaporized from the downflowing stream of liquid isobutane absorbent. To reduce the volume of gas being handled in the second tower 31, as well as to assist in control of temperature in tower 11, the overhead gas in line 15 is cooled in condenser 32 to a temperature such that the greater portion of the isobutane is condensed to the liquid state and is then passed through line 34 to receiver 35 from which the condensed isobutane is removed through line 36 and pumped by means of pump 37 to distributing line 39. From distributing line 39, the condensed isobutane is passed through a plurality of lines indicated by lines 40, 41, 42, and 44 to a plurality of points in the tower 11. By means of this system of distributing the condensed isobutane to a plurality of points in the tower 11, not only is temperature control assisted, but, in addition, the desired ratio of isobutane to propylene dissolved therein is maintained without feeding excessive volumes of isobutane to the tower 11 from feed line 14 in order to compensate for evaporation of isobutane as the liquid stream descends through the tower and as assurance that the proper isobutane-propylene ratio will be maintained at the bottom of the tower.

The remaining portion of the overhead gas in receiver 35 is removed through line 45 and pumped by means of compressor 46 to tower 31. Tower 31 will usually be operated at a higher pressure than tower 11, and, to remove the heat of compression from the incoming gas, cooler 47 is provided in line 45. Tower 31 is of the bubble plate type modified to the extent that each plate is provided with a time tank to obtain sufficiently long time of contact of dissolved gas and liquid isobutane absorbent for effective absorption-alkylation. Liquid isobutane absorbent containing dissolved aluminum bromide enters the top of the tower through line 49 and passes downwardly through the tower accumulating on the plates illustrated by plate 50. The ascending gas passes through bubble caps 51 to obtain intimate contact of gas and liquid. The accumulated liquid on each plate passes to a time tank, illustrated by time tank 52, through line 54 provided with pump 55 and, after suitable residence time in the tank, is returned to the tower through line 56 to flow to the next successively lower plate. To maintain proper temperature control in the tower 31, the liquid in the time tanks may be cooled by providing suitable cooling means (not shown) such as a cooler within the tanks or by circulating the liquid within the tank through an external cooler.

Reaction conditions within the tower 31 are maintained suitable for alkylation of the isobutane with the ethylene. A small amount of propylene will also be contained in the ascending gas and, because of the greater alkylating activity of the propylene, will alkylate the isobutane under the conditions favorable for reaction with the ethylene. Suitable alkylating conditions in tower 31 are: aluminum bromide concentration in the isobutane—3.0 weight per cent; temperature—130° F.; pressure—265 p. s. i. a.; residence time of liquid per equilibrium contact space—30 minutes.

The rich liquid effluent leaves tower 31 through line 57 and contains excess isobutane absorbent, isobutane-ethylene alkylate consisting essentially of 2,3 dimethyl butane, small amount of isobutane-propylene alkylate, some absorbed but unreacted ethylene and perhaps traces of propylene, and some propane, ethane, and methane. The effluent is treated in similar manner to the effluent from tower 11 by passing to flash evaporator 59. The light gases are taken overhead through line 60, while the bottoms containing the aluminum bromide and any tar formed during the reaction pass to gravity settler 61. The tar is withdrawn from the settler through line 62, and the aluminum bromide concentrate is taken overhead through line 64 and recycled to line 49 for admixture with isobutane and reuse in tower 31. The overhead from evaporator 59 in line 60 is sent to a suitable fractionation column 65 for separation of the light gases which discharge through line 66. The isobutane is separated from the alkylate product in fractionator 67 and recycled after condensation (not shown) through line 14. The alkylate product is drawn off from the fractionator 67 through line 70 for final stabilization and treatment.

The overhead isobutane from fractionators 29 and 67 admixes with fresh liquid isobutane entering the system through line 71 and passes through line 14 to towers 11 and 31. The aluminum bromide concentrate from settlers 21 and 61 admixes with the isobutane entering towers 11 and 31 respectively, but additional aluminum bromide

must usually be added thereto to bring the concentrations to the desired value for each tower. Suitable adjustment of the aluminum bromide concentration of the isobutane entering tower 31 may be effected by adding a concentrated solution of aluminum bromide in isobutane from reservoir 71 to the isobutane stream in line 49. In similar manner the aluminum bromide concentration of the isobutane solution entering tower 11 may be adjusted by passing aluminum bromide concentrate from reservoir 72 to line 14.

The overhead gases from the tower 31 pass through line 74 and will contain an appreciable portion of the isobutane absorption menstruum. This gas stream is then sent to a third absorption tower 75 wherein the gas is contacted with a conventional light absorption oil having a molecular weight considerably in excess of that of the isobutane, say from 160 to 240, introduced through line 76. Absorption tower 75 may be of the conventional bubble plate type wherein the downcoming oil collects on the successive plates 77 and then flows through the respective down-comers 79 to the next succeeding plate while the ascending gas rises through the bubble caps 80 on each successive plate. The gas overhead, free of isobutane, leaves tower 75 through line 81 and is suitable for use as a fuel gas. The rich absorption oil bottoms in line 82 are then sent to stripping column 84, wherein the absorbed isoparaffin is stripped from the oil by steam introduced through line 85. The steam-isoparaffin overhead in line 86 is condensed in condenser 87 and sent to separator 89. Water is removed from the bottom of separator 89 through line 90. Recovered isobutane is removed through the separator 89 through line 91 and recycled to the towers 11 and 31.

Various modifications may be made in the above described procedure. For example, where the gas streams in lines 27 and 66 from fractionating columns 26 and 65, respectively, contain more than insignificant amounts of olefins, the streams may be passed to olefin feed line 10 for recycle through the system. In such case, the light gases contained in these streams will be removed from the system along with the major portion of the light gases contained in the original gas feed through line 81 from absorber 75. This and other modifications will be readily apparent to those skilled in the art.

The particular operating conditions for selective absorption-alkylation of the propylene and absorption-alkylation of the ethylene may be varied from those given hereinabove. However, while the operating conditions for selective absorption-alkylation of the propylene may be varied, they are somewhat more critical than the operating conditions for absorption-alkylation of the ethylene. This arises from the fact that not only is the propylene to be selectively absorbed and alkylated, but also from the necessity for correlating temperature and catalyst concentration, particularly where aluminum bromide catalyst is employed, in order to minimize the tendency of the propylene to polymerize in the presence of the catalyst. Where aluminum bromide is the catalyst employed and isobutane is the absorption menstruum, the temperature and catalyst concentration may be correlated in accordance with the disclosure of copending application Serial No. 618,324, filed September 24, 1945. Temperatures to be employed for selective absorption-alkylation of propylene are preferably between about 35° F.

and 150° F., and for these temperatures the following minimum concentrations of aluminum bromide in isobutane absorption menstruum, as determined by the disclosure of the above-mentioned copending application, may be employed:

Temperature—°F.	Weight Per Cent of AlBr ₃ in Isobutane Absorption Menstruum
35°	2.1 to 4.2
60°	0.8 to 1.6
90°	0.4 to 0.8
120°	0.3 to 0.6
150°	0.2 to 0.4

The concentrations given above are minimum concentrations. Higher concentrations may also be employed although the use of higher concentrations tends to be uneconomical. Pressures of 60 to 250 pounds per square inch absolute may be employed for selective absorption-alkylation of the propylene. In order to provide for most efficient absorption and alkylation of the propylene, the rate of flow of the isobutane absorption menstruum should be such that for each equilibrium absorption contact, or, as otherwise expressed, for each theoretical plate or equivalent theoretical transfer unit, a residence time of 0.5 to 20 seconds, preferably 3 to 10 seconds, is obtained. However, longer residence times may be employed if desired, but in such cases ethylene will begin to react along with the propylene to more than a minor extent, thereby resulting in a decreased yield of ethylene alkylate in the second zone. Also, a ratio of isobutane absorption menstruum to feed gas should be employed such that there will be at least 40 mols of isobutane to each mol of propylene dissolved in the absorption menstruum at each point in the absorption-alkylation reaction zone. The number of equilibrium absorption contacts required will depend upon the size and type of packing, the ratio of liquid to gas, the rate at which the propylene reacts with the isoparaffin under the reaction conditions employed, and the temperature and pressure employed, and may be readily determined by those skilled in the art.

For absorption-alkylation of the ethylene, temperatures of about 50° F. to 200° F., preferably 65° F. to 150° F., may be employed. The pressures to be employed are preferably higher than those employed for absorption-alkylation of propylene and may be from 200 to 400 pounds per square inch absolute or higher, for example, as high as 700 pounds per square inch absolute. The concentration of dissolved aluminum bromide in the isobutane absorption menstruum may be from 0.1 to 12.0 weight per cent, or somewhat higher. The residence time of liquid per equilibrium absorption contact may be between 1 and 30 minutes. The mol ratio of isobutane absorption menstruum to dissolved ethylene may be as low as 1 to 1. The number of equilibrium contacts to be employed are subject to the same considerations mentioned above in connection with propylene.

If desired, an alkylation promoter such as hydrogen bromide may be employed for absorption-alkylation of both the propylene and the ethylene, but the use of a promoter will usually be most advantageous for absorption-alkylation of the ethylene.

The process is adapted for use with gas streams containing from a few per cent of olefin up to as

high as 50 or 60 per cent and is of utility for a light olefin stream contaminated with considerable proportions of methane or hydrogen or both. Pure isoparaffin streams or a single pure isoparaffin need not necessarily be employed as the absorption menstruum.

A stream of isobutane may be employed, or a stream of isopentane, or a stream of mixed isobutane-isopentane is satisfactory. Normal paraffins may also be present, although, if present, provision should be made to remove these normal paraffins in the fractionation system as rapidly as they are introduced in the make-up isoparaffin absorption menstruum to prevent build-up of these components in the absorption-reaction system. Small amounts of heavier paraffins, i. e., paraffins or isoparaffins having six or more carbon atoms may also be present and have the advantage of raising the average molecular weight of the absorption menstruum, thereby reducing its volatilization.

Alkylate product introduced with the recycle catalyst stream is one source of such heavier hydrocarbons would tend to undergo competing reactions with the olefin in the presence of the catalyst; however, their concentration should be low, less than 20 mol per cent, preferably less than 10 mol per cent; and in all cases less than one-half the molar quantity of isoparaffin, preferably considerably less.

As hereinbefore mentioned, the process may be carried out in a single tower; but it is preferred to use two towers in order to obtain the benefits of operating the second tower at a higher pressure than the first tower. Nevertheless, satisfactory results may be obtained with the use of a single tower. In such cases, the ethylene-isoparaffin alkylate may be removed from the tower at a point intermediate from the top of the tower and the point where the propylene-isoparaffin alkylate is removed. Additionally, in such cases, isoparaffin absorption menstruum may be added to the tower at a plurality of points and at different rates in order to obtain the desired isoparaffin-olefin ratio in the zone where the propylene is reacted and in the zone where the ethylene is reacted. Further, the temperature and the concentration of catalyst in the absorption menstruum may be varied in both zones for most efficient absorption-alkylation.

The following example will illustrate the results to be obtained from the process of the invention:

A gas of the following composition was passed upwardly through a tower constructed of sixteen feet of six-inch pipe packed with five-eighths inch Raschig rings:

Component	Volume Per Cent
Methane	87.31
Ethylene	10.65
Propylene	2.04

Isobutane at 60° F. containing 0.8 weight per cent of dissolved aluminum bromide was passed downwardly through the tower. The mol ratio of isobutane entering the tower to lean gas leaving the tower was 0.5, and the pressure within the tower was maintained at 100 pounds per square inch absolute. In passing through the packed section, 83% of the propylene was removed, while less than 2% of the ethylene was removed. Thus, the olefin content of the gas

leaving the tower consisted of 10.44 volumes of ethylene to 0.35 volume of propylene or a ratio of ethylene to propylene of 29 to 1, as compared with a ratio of 5 to 1 in the feed gas. An even larger proportion of the propylene could be removed by the use of a tower containing a greater length of packing. Alkylation-absorption of the gas leaving the packed tower in a bubble-plate column produced an isobutane-ethylene alkylate product consisting largely of 2,3 dimethyl butane and, because of the small quantity of propylene in the gas, containing only a minor amount of isobutane-propylene alkylate.

While I have thus described my invention, it is to be understood that such description has been given by way of illustration and example only and not by way of limitation, reference for the latter purpose being had to the appended claims.

I claim:

1. A process for the recovery and utilization of propylene and ethylene contained in a gaseous stream of light hydrocarbons which comprises passing said stream into a first absorption column, passing through said absorption column countercurrently to said gaseous stream a homogeneous, single phase stream of absorption oil consisting essentially of liquid isoparaffin hydrocarbons of not more than five carbon atoms and containing dissolved aluminum bromide in a concentration of between about 0.2 and 4.2 weight per cent in quantity such that the mol ratio of isoparaffin absorption oil to dissolved propylene will be at least 40, maintaining a temperature between 35° F. and 150° F. and a pressure between 60 and 250 pounds per square inch absolute in said column, removing from said column a stream of rich absorption oil containing alkylate product of said isoparaffin absorption oil and propylene, passing the lean gaseous effluent from said column to a second absorption column, passing through said second absorption column countercurrently to the stream of said gaseous effluent a homogeneous, single phase stream of absorption oil consisting essentially of liquid isoparaffin hydrocarbons of not more than five carbon atoms and containing dissolved aluminum bromide in a concentration of between about 0.1 and 12.0 weight per cent in quantity such that the mol ratio of isoparaffin absorption oil to dissolved ethylene will be at least 1, maintaining a temperature between 50° F. and 200° F. and a pressure between 200 and 700 pounds per square inch absolute in said second column, removing from said column a stream of rich absorption oil containing alkylate product of said isoparaffin absorption oil and ethylene, separating aluminum bromide, absorption oil, and alkylate product from each of said rich absorption oils, dissolving said aluminum bromide in said absorption oil and recycling to said absorption columns, separately recovering said separated alkylate products, passing gaseous overhead from said second absorption column through a third absorption column countercurrently to an essentially paraffin hydrocarbon oil having an average molecular weight considerably in excess of that of isobutane, stripping absorbed isoparaffin from rich liquid absorption oil effluent from said third absorption column, and recycling stripped isoparaffin absorption oil to said first and second absorption columns.

2. A process for the recovery and utilization of propylene and ethylene contained in a gaseous stream of light hydrocarbons which comprises

passing said stream into a packed absorption column, passing through said absorption column countercurrently to said gaseous stream a homogeneous single phase stream of absorption oil consisting essentially of liquid isobutane and containing dissolved aluminum bromide in a concentration of between about 0.2 and 4.2 weight per cent in quantity such that the mol ratio of isobutane absorption oil to dissolved propylene will be at least 40, maintaining a temperature between 35° and 150° F. and a pressure between 60 and 250 pounds per square inch absolute in said column, removing from said column a stream of rich absorption oil containing alkylate product of said isobutane absorption oil and propylene consisting essentially of heptanes, passing lean gaseous effluent from said column to a bubble plate column, passing through said bubble plate column countercurrently to said stream of gaseous effluent a homogeneous, single phase stream of absorption oil consisting essentially of liquid isobutane and containing dissolved aluminum bromide in a concentration of between about 0.1 and 12 weight per cent in quantity such that the mol ratio of isobutane absorption oil to dissolved ethylene will be at least 1, maintaining a temperature between 50° F. and 200° F. and a pressure between 200 and 700 pounds per square inch absolute in said column, removing from said column a stream of rich absorption oil containing alkylate product of said isobutane absorption oil and ethylene consisting essentially of 2,3-dimethylbutane, separating aluminum bromide, absorption oil, and alkylate product from each of said rich absorption oils, dissolving said aluminum bromide in said absorption oil and recycling to said packed column and bubble plate column, separately recovering said separated alkylate products, passing gaseous overhead from said bubble plate column through an absorption column countercurrently to an essentially paraffin hydrocarbon oil having an average molecular weight considerably in excess of that of isobutane, stripping absorbed isobutane from rich liquid absorption oil effluent from said absorption column, and recycling stripped isobutane to said packed column and said bubble plate column.

3. A process for the recovery and utilization of propylene and ethylene contained in a gaseous stream of light hydrocarbons which comprises passing said stream into a first absorption column, passing through said absorption column countercurrently to said gaseous stream a homogeneous, single phase stream of absorption oil consisting essentially of liquid isoparaffin hydrocarbons of not more than five carbon atoms and containing dissolved aluminum bromide in a concentration of between about 0.2 and 4.2 weight per cent in quantity such that the mol ratio of isoparaffin absorption oil to dissolved propylene will be at least 40, maintaining a temperature between 35° F. and 150° F. and a pressure between 60 and 250 pounds per square inch absolute in said column, removing from said column a stream of rich absorption oil containing alkylate product of said isoparaffin absorption oil and propylene, passing the lean gaseous effluent from said column to a second absorption column, passing through said second absorption column countercurrently to the stream of said gaseous effluent a homogeneous, single phase stream of absorption oil consisting essentially of liquid isoparaffin hydrocarbons of not more than five carbon atoms and containing dissolved aluminum bromide in a concentration of between about 0.1 and 12.0 weight per cent in quantity such that the mol ratio of isoparaffin absorption oil to dissolved ethylene will be at least 1, maintaining a temperature between 50° F. and 200° F. and a pressure between 200 and 700 pounds per square inch absolute in said second column, removing from said column a stream of rich absorption oil containing alkylate product of said isoparaffin absorption oil and ethylene, separating aluminum bromide, absorption oil, and alkylate product from each of said rich absorption oils, dissolving said aluminum bromide in said absorption oil and recycling to said absorption columns, separately recovering said separated alkylate products, passing gaseous overhead from said second absorption column through a third absorption column, passing through said third absorption column countercurrently to an essentially paraffin hydrocarbon oil having an average molecular weight considerably in excess of that of isobutane, stripping absorbed isoparaffin from rich liquid absorption oil effluent from said third absorption column, and recycling stripped isoparaffin absorption oil to said first and second absorption columns.

4. A process for the recovery and utilization of propylene and ethylene contained in a gaseous stream of light hydrocarbons which comprises

per cent in quantity such that the mol ratio of isoparaffin absorption oil to dissolved ethylene will be at least 1, maintaining a temperature between 50° F. and 200° F. and a pressure between 200 and 700 pounds per square inch absolute in said second column, removing from said column a stream of rich absorption oil containing alkylate product of said isoparaffin absorption oil and ethylene, separately recovering said alkylate products from said rich absorption oils, passing gaseous overhead from said second absorption column through a third absorption column countercurrently to an essentially paraffin hydrocarbon oil having an average molecular weight considerably in excess of that of the absorption oil employed in said first and second columns, stripping absorbed isoparaffin absorption oil from rich liquid absorption oil effluent from said third absorption column, and recycling stripped isoparaffin absorption oil to said first and second absorption columns.

4. A process for the recovery and utilization of propylene and ethylene contained in a gaseous stream of light hydrocarbons which comprises passing said stream into a first absorption column, passing through said absorption column countercurrently to said gaseous stream a homogeneous, single phase stream of absorption oil consisting essentially of liquid isoparaffin hydrocarbons of not more than five carbon atoms and containing dissolved aluminum bromide in a concentration of between about 0.2 and 4.2 weight per cent in quantity such that the mol ratio of isoparaffin absorption oil to dissolved propylene will be at least 40, maintaining a temperature between 35° F. and 150° F. and a pressure between 60 and 250 pounds per square inch absolute in said column, removing from said column a stream of rich absorption oil containing alkylate product of said isoparaffin absorption oil and propylene, passing the lean gaseous effluent from said column to a second absorption column, passing through said second absorption column countercurrently to the stream of said gaseous effluent a homogeneous single phase stream of absorption oil consisting essentially of liquid isoparaffin hydrocarbons of not more than five carbon atoms and containing dissolved aluminum bromide in a concentration of between about 0.1 and 12.0 weight per cent in quantity such that the mol ratio of isoparaffin absorption oil to dissolved ethylene will be at least 1, maintaining a temperature between 50° F. and 200° F. and a pressure between 200 and 700 pounds per square inch absolute in said second column, removing from said column a stream of rich absorption oil containing alkylate product of said isoparaffin absorption oil and ethylene, removing aluminum bromide as a concentrate separately from each of said rich absorption oils, separately recovering said alkylate products from said rich absorption oils, dissolving said aluminum bromide concentrate in the remainder of the absorption oils and recycling to said absorption columns, passing gaseous overhead from said second absorption column through a third absorption column countercurrently to an essentially paraffin hydrocarbon oil having an average molecular weight considerably in excess of that of the absorption oil employed in said first and second columns, stripping absorbed isoparaffin absorption oil from rich liquid absorption oil effluent from said third absorption column, and recycling stripped isoparaffin absorption oil to said first and second absorption columns.

5. A process for the recovery and utilization of propylene and ethylene contained in a gaseous stream of light hydrocarbons which comprises passing said stream into a packed absorption column, passing through said absorption column countercurrently to said gaseous stream a homogeneous single phase stream of absorption oil consisting essentially of liquid isoparaffin hydrocarbons of not more than five carbon atoms and containing dissolved aluminum bromide in a concentration of between about 0.2 and 4.2 weight per cent in quantity such that the mol ratio of isoparaffin absorption oil to dissolved propylene will be at least 40, maintaining a temperature between 35° F. and 150° F. and a pressure between 60 and 250 pounds per square inch absolute in said column, removing from said column a stream of rich absorption oil containing alkylate product of said isoparaffin absorption oil and propylene, removing lean gaseous effluent from said packed column, removing from said lean gaseous effluent vaporized isoparaffin absorption oil, recycling said removed isoparaffin absorption oil to said packed absorption column, passing said lean gaseous effluent to a bubble plate column, passing through said bubble plate column countercurrently to said stream of gaseous effluent a homogeneous, single phase stream of absorption oil consisting essentially of liquid isoparaffin hydrocarbons of not more than five carbon atoms and containing dissolved aluminum bromide in a concentration of between about 0.1 and 12 weight per cent in quantity such that the mol ratio of isoparaffin absorption oil to dissolved ethylene will be at least 1, maintaining a temperature between 50° F. and 200° F. and a pressure between 200 and 700 pounds per square inch in said bubble plate column, removing from said column a stream of rich absorption oil containing alkylate product of said isoparaffin absorption oil and ethylene, separating aluminum bromide, absorption oil, and alkylate product from said rich absorption oils, separately recovering said separated alkylate products, dissolving said aluminum bromide in said absorption oil and recycling to said packed and bubble plate columns, passing gaseous overhead from said bubble plate column through a third absorption column countercurrently to an essentially paraffin hydrocarbon oil having an average molecular weight considerably in excess of the isoparaffin absorption oil employed in said packed and bubble plate columns, stripping absorbed isoparaffin absorption oil from rich liquid absorption oil effluent from said third absorption column, and recycling stripped isoparaffin absorption oil to said packed and bubble plate columns.

CHARLES OVID BAKER.
